UNITED STATES PATENT OFFICE

2,556,175

BRIDGE AND MOBILE LAUNCHING STRUCTURE THEREFOR

Lester P. Frost, United States Army,
Fort Belvoir, Va.

Application June 12, 1945, Serial No. 599,040

16 Claims. (Cl. 14—1)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to bridges, particularly mobile bridges having pivotally connected sections, and means operably rotating the respective sections around the respective pivot point to launch and retrieve the bridge.

It is an object of this invention to provide a bridge carried by a vehicle possessing means for rapidly launching and retrieving the bridge with a minimum crew.

It is another object of this invention to provide a scissor or jack-knife-type bridge construction transported by a trailer containing actuating mechanism for launching the bridge across an open span in the terrain.

Another object of this invention is to provide a bridge of the class herein described mounted on a trailer provided with rear steering means to aid in transversing narrow winding road and sharp curves.

Another object of this invention is to provide a bridge of the class herein described having extensible floor beams.

Another object of this invention is to provide a bridge of the class herein described folded upon a trailer, pivoted to the rear thereof for launching, and counterbalanced with a prime mover coupled to the trailer.

Still another object of this invention is to provide a scissor-type bridge with one section thereof pivoted to a trailer containing hoist means raising the bridge from the trailer body and swinging the bridge around its pivot to a point slightly beyond vertical.

A further object of this invention is to provide means for opening the far section of a scissor-type bridge independently of the means for lowering the near section of the bridge.

A further object of this invention is to provide reversible opening and lowering means for a scissor-type bridge so that the opening and lowering means may function as closing and raising means.

A further object of this invention is to provide a bridge of the class herein described removably pivoted to a transporting vehicle.

A further object of this invention is to provide a bridge of the class herein described mounted on a trailer releasably coupled to a prime mover whereby said trailer may be employed as an approach ramp to the bridge.

A still further object of this invention is to

2

provide a bridge of the class herein described comprising two like sections pivotally secured together whereby the bridge may be launched and retrieved from either end.

5 It is also an object of this invention to provide a bridge of the class described pivotally secured to any launching structure.

It is a further object of this invention to provide a bridge of the class herein described comprising a multiplicity of interchangeable parts which may be transported individually or collectively and assembled rapidly and easily at any desired location.

The foregoing and other objects of this invention will be more apparent from reading the specification in conjunction with the drawings, forming a part thereof, wherein:

Fig. 1 is a perspective view of the bridge in folded condition upon the transporting trailer with the prime mover attached thereto;

Fig. 2 is a perspective view of the bridge in partially launched position with the opening cable contacting the boom sheaves;

Fig. 3 is a perspective view of the bridge in partially retrieved position with the opening cable out of contact with the boom sheaves;

Fig. 33 is a side elevation of the structure shown in Fig. 30, parts omitted to show more clearly the connection between the hydraulic reservoir and the suction side of the hydraulic pump;

Fig. 34 is a perspective view of the control panel as seen from the left side of the operator's platform;

Fig. 35 is a perspective view of the control panel from the center of the operator's platform;

Fig. 36 is a side elevation of the control panel, parts shown in section;

Fig. 37 is a rear elevation of the control panel, parts shown in section;

Fig. 38 is a top plan view of a portion of the rear of the trailer showing the relationship between the bridge opening cable and guiding sheaves;

Fig. 39 is a vertical section taken on line 39—39 of Fig. 38;

Fig. 40 is a horizontal section of the swivel sheave taken on line 40—40 of Fig. 39; and

Fig. 41 is a perspective view of the trailer-prime mover counterbalance couple.

In the drawings wherein like members are given the same reference numeral, the invention comprises, generally, a bridge 3, Figs. 1 and 2, pivotally mounted to a mobile vehicle 2, it being clearly understood, of course, that the bridge may be utilized on permanently placed launching structures as well as mobile structures. The mobile vehicle may be any powered vehicle, but preferably it is a prime mover 1 having a trailer 2 secured thereto, as it is contemplated within the invention to utilize the trailer as an approach ramp to the bridge 3 when the trailer is disconnected from the prime mover 1. The bridge 3 may be viewed generally as any bridge, such as a girder or truss-type bridge, divided and pivoted together at the middle; preferably, however, the bridge, is formed of two longitudinally extending half sections. For the purposes of illustration and description, the section pivotally secured to the trailer or other launching emplacement is designated as the near section 5, whereas the freely swinging section is designated the far section 6. These two half sections are, preferably, identical in construction and have interengaging brackets 7 and 8 pivotally connected by a pin 9, Figs. 14 and 18, inserted therethrough at a point beneath the lower surface of the bridge to provide a scissor-type, substantially symmetrical bridge. The near section of the bridge 5 is releasably pivoted to the rear portion of the trailer frame; thus the bridge may be folded upon the trailer for transporting. Hoist means 10, Figs. 2 and 3, are provided on the trailer for raising the bridge in a folded condition to a point where the center of gravity of the bridge is beyond the trailer-to-bridge pivot point. Separate means 11 are provided for holding and lowering the near section of the bridge and for opening the far section of the bridge to form a continuous bridge surface.

As previously stated, any conventional bridge structure may be used in practicing this invention. It has been found to be advisable, however, to employ a modified through-girder type bridge, preferably constructed of aluminum. This is the type construction illustrated in the drawings and described hereinafter. For spanning relative long distance, such as 80 to 160 feet, it has been found desirable to construct the component parts of the bridge with aluminum in order to obtain a high strength-weight ratio. Since each of the two sections of this new girder bridge is identical, the specific details of construction will be described for only one section.

The principal support of the bridge load is provided by two girders 11, Figs. 5 and 8, each of which comprises top and bottom flanges 12, web sheet or sheets 14, positioned in the flanges 12, and stiffeners 15 spaced along and connected with the top and bottom flanges 12 of each girder 11. Preferably, the stiffeners 15 are angle members arranged in parallel pairs, one on each side of the web 14. When the stiffeners 15 extend between the extending flanges 12a of the top and bottom flanges 12, suitable filler plates or spacers 16 are positioned intermediate the stiffeners 15 and the web 14. Cover plates 17 may be placed on either or both of the top and bottom flanges 12 if desired.

Connecting the girders are transverse floor beams 18, preferably formed of I-beams having portions of the flanges cut out on one side of the I-beam web and positioned in a manner such that the web 18a of the I-beam contacts the extending leg 15a of the inside stiffener 15 and is fastened thereto. The other side of the I-beam web 18a is fastened to the web 14 of the girder 11 by an angle member 19 secured thereto. In order that the bridge may be transported in a minimum space and extended after launching, the floor beams are formed of two half sections 20 and 21, Figs. 9 to 12, inclusive, each secured to a separate girder. Channel members 22 are positioned on each side of the floor beams and rigidly secured to one section 20 thereof. These channel members 22 extend along the other section 21 which has a longitudinal slot 23 therein, adapted

to receive a bolt 24 inserted therethrough and extending through aligned apertures 26 provided in the channel members 22. The bolt is retained in the channel members 22 by the head 24a of the bolt 24 which contacts the outer surface of one channel member 22 and a nut 25 engaging the bolt which contacts the outer surface of the other channel member 22. Interposed between the flanges of the slotted floor beam section 21 and the channel members 22 extending therealong are bearing slides 27 secured to the I-beams. These slides 27 are preferably chamfered at the ends in a conventional manner for bearing slides.

To separate the floor beam sections thereby increasing the length of the floor beam and hence the width of the bridge, a gear box 28 is secured to the slotted beam section 21 and operates a screw shaft 29 terminally secured to one of the channel members 22 in any suitable manner such as an angle bracket 30. The gear box 28 is adapted for manual operation by turning a substantially T-shaped crank having a polygonal socket (not shown) engaging a polygonal-headed shaft 31 having a pinion gear 32 positioned thereon intermeshing with a gear 33 positioned on and operably engaging the screw shaft 29. It is not necessary to provide gear boxes on each floor beam, two for each bridge section measuring forty feet has proved to be adequate.

A series of stringer assemblies are provided to span the gap between adjacent floor beam sections 20 and 20, or 21 and 21, respectively. Each of these stringer assemblies comprises longitudinal stringers and transverse beams. One of the longitudinal stringers, called the curb-supporting stringer 34 for the purposes of description, is in the form of a channel member having a section cut out of the lower edge of each end so that the channel member may be extended over and to the midpoint of the floor beam 18 and support a curb member 35 bolted thereon. The curb members are provided with flanged ends 35a for bolting each curb section to the adjacent curb section through a curb divider 36 positioned between adjacent curb sections and secured to the stiffeners 15 and floor beam 18. The other longitudinal stringer 37 is in the form of a channel member positioned near midpoint of the floor beam 18 and between adjacent similar floor beam sections in a manner such that its top surface is in the same plane as the top surface of the floor beam 18. The transverse beams 38 are preferably a plurality of I-beams positioned intermediate the longitudinal stringers 34 and 37 and have their top surfaces in the plane of the top surface of the floor beams 18. The transverse beams 38, Figs. 3, 18 and 19, are secured to the longitudinal stringers 34 and 37 in any suitable manner, such as welding and riveting. If it is desired, however, to retain the bridge in a condition for rapidly disassembling, angle members 39 may be bolted to the longitudinal stringers 34 and 37 and transverse beams 38 to provide a connecting link between the two parts. Likewise, angle members 40, Figs. 8, 9 and 11, may be employed as the connecting link between the top of the floor beam 18 and the curb-supporting stringer 34. An angle member 41, Figs. 22 to 24, inclusive, may be employed as the connecting link between the longitudinal stringer 37 and the channel member 22 rigidly secured to the floor beam section 20; and, an angle member 42 may be employed to connect the longitudinal stringer 37 to a saddle bracket 44 positioned interme-

diate the bearing slide 27 and the top flange of the slotted floor beam section 21. Lift brackets 45 and 45a, Fig. 5, in the form of spaced members 46 supporting a pin 47 therebetween are positioned in the bridge, preferably between the pivot end floor beam 18 and adjacent transverse beams 38 and between the approach end floor beam 18 and the adjacent transverse beams 38, respectively. These lift brackets 45 and 45a are designed to engage operably the hooks provided on the lifting cables 50, Figs. 2 and 3.

Diagonal sway braces 51, Fig. 5, are positioned between the longitudinal stringers. These sway braces 51 are connected in any suitable manner, preferably through angle members 52, to the longitudinal stringers 34 and 37 respectively. The sway braces 51 are positioned in a manner such that they are beneath the transverse beams 38 and in contact therewith so that they may be secured thereto. Since each bridge section may be viewed as two longitudinal half sections due to the extensibility of the floor beams 18, the sway braces 51 are positioned to effect a triangular support arrangement in each longitudinal half section to increase rigidity of the bridge structure.

The two ends of the bridge section may be appropriately termed the approach end, meaning that end from which one approaches the bridge, and the pivot end, designating that end of the bridge section pivotally secured to the other bridge section. The pivot end of each bridge section is provided with bracket plates secured to each side of the girder web which extend outwardly and downwardly therefrom. The bracket 7, Figs. 1, 14, 15 and 17, comprises plates secured to one of the girders and flared outwardly at the extending end so as to increase the space therebetween; whereas the bracket 8 comprises plates secured to the other girder and unflared. Since each of the bridge sections is identical in construction, the flared bracket plates 7 on one section receive the unflared bracket plates 8 of the other bridge section. These bracket plates are provided with apertures 4 adapted to align and receive a pivot pin or shaft 9 inserted therethrough. The design of the brackets and position of the apertures 4 are such that when pivoted together, the pivot point of the bridge is spaced from and slightly below the bridge structure so as to provide a clearance between the respective members of the bridge section during pivotal operation. A portion of the lower or bottom girder flanges must be cut out to afford clearance for the downwardly extending portion of the bracket plates 7 and 8. This necessitates the pivot end floor beam 18 being suspended slightly differently from the others hereinbefore described. This beam is supported by angle members 53 and 53a, Figs. 18 and 19, secured on each side of the beam web 18a, one of which angle members 53a is secured to the pivot bracket plate 7 or 8 and the other of which angle members 53 is secured to the girder web 14. An additional support is provided in the form of a triangular support plate 55 having a flanged side portion 56 secured to the floor beam web 18a and another side secured to the extending leg of an angle member 57 secured to the girder. Likewise, the curb-supporting stringer 34 extends beyond the floor beam 18 to the bridge center. Hence, the curb divider 36, Figs. 5 to 8, inclusive, positioned on this beam 18 is smaller than the others so that it may fit inside the curb-supporting stringer 34 and curb member 35 when the extending flanges of these

members are recessed to receive the divider 36. The top portion of the girder web has secured to each side spacer plates 60, Figs. 14 to 16, inclusive, supporting bracket plates 61 having outward and downward projections 62 and 63, respectively, and portions of the bridge web contained between the bracket plates 61 are cut out to effect a recess 64 into which is positioned a sheave 65 supported by a pin 66 inserted through the plates 61.

The downwardly extending projections 63 on the two bridge sections are in contact when the bridge is fully extended. An angle member 67 is positioned over the top and bottom bracket plates 61 and 7 and 8 respectively, and angle members 67a are positioned intermediate the two bracket plates. Suitable filler plates 16, Fig. 5, are positioned between the girder web 14 and angle member 67 and 67a, Figs. 13 and 14. On top of the girder 11 and just back of the sheave 65 is a channel member 68 supporting a pin 69 and adapted to engage an eyelet or hook 49 secured to the bridge opening and closing cable 70. These pins 69 when not engaging the opening and closing cable 70 serve as guides for said cable and it is therefore advisable to position a small sheave on the pin 69 to decrease the wear on the cable. Appropriate guide members 71 may be positioned on the face of the girders if desired.

The approach end of the bridge has a portion of the girder web 14 extended upwardly, and plates 74, Figs. 23 and 24, securely fastened to each side thereof. These plates 74 extend upwardly defining a channel 75, Figs. 20 and 21, therebetween in the lower portion where the girder web 14 is removed. Rigidly secured to the upwardly extending plates is a pivot member 76, Figs. 20 to 23, inclusive, having a lipped groove provided therein and adapted to receive a pin member 194 on the trailer 2 to effect a releasable pivot connection between the bridge and trailer, as will be discussed more fully hereinafter. This pivot member 76 may be described as a single unit, since it may be easily constructed as a single unit, in the form of a block member having a portion thereof cut out to form a flared groove 77 substantially parallel to the bridge deck surface, and an arcuate aperture 78 extending upwardly of said groove effecting a lip 79 on the upper portion thereof. The lower portion of the pivot member is channeled to receive a safety stop 80 pivotally mounted therein and adapted to restrict or open selectively the groove 77 whereby the pivot pin 194, Figs. 26 and 27, may be retained in the arcuate aperture 78 or removed therefrom. Since this end of the bridge bears the total weight of the bridge during launching and it is also contemplated to launch another bridge from this bridge section, it is desirable to reinforce this end of the bridge. A divided floating beam 81, Figs. 22, 24 and 25, is connected, therefore, to the bridge structure and spaced from the main floor beam 18 of the approach end of the bridge. These two beams 81 and 18 are covered on the under surface with a divided bearing plate 82 to provide a bearing surface with sufficient area to support the bridge on any type terrain, as well as providing easy extensibility of the bridge. Positioned on top of the girder near the pivot member is a bracket 83, Figs. 20 and 21, similar to the cable engaging bracket on the pivot end. The bracket 83 serves as a cable guide when the bridge is near extended position, and as a yoke bracket for tying two bridges together. Positioned outside the girder

is a bracket 84 adapted to receive a yoke employed in securing two such bridges together.

The deck surface 85 of the bridge may be of any suitable material such as wooden planks or aluminum grill work. The deck plate members are preferably formed in units adapted to cover the space between adjacent floor beam sections 20 and 20 or 21 and 21, respectively, Fig. 9, and have the width of substantially half the bridge. 10 These deck plate units may be secured to the bridge with angle members 86, Fig. 6, extending downwardly therefrom and positioned to contact angle members 86a extending from the longitudinal stringers 34 and 37, Figs. 5, 6 and 11, 15 each of said angle members being apertured to receive a bolt and nut assembly 87 when aligned.

Eyelets 88 are secured to the main floor beam at the approach end of the bridge and receive studs extending downward from portable approach ramps employed when the trailer is disconnected from the bridge.

As previously stated, any mobile vehicle may be employed to transport and launch this bridge, or the bridge may be used on permanently emplaced launching structures. Since mobility is a desirable feature of this bridge structure, and it is contemplated employing the transporting vehicle as an approach ramp, a trailer 2 of the general semi-trailer design has been found to be the most appropriate and desirable transporting vehicle and launching structure. The trailer has a suitable number of longitudinal supports 90, Fig. 28, preferably in the form of I-beams or girders, which are connected by suitably positioned transverse beams 91. The webs of the longitudinal and transverse beams are provided with suitable apertures to permit movement of the necessary parts therethrough.

The trailer is supported in operable position at 40 the front by a conventional fifth wheel arrangement 92, Fig. 1, connecting the trailer 2 to the prime mover 1. Hydraulic or mechanical jacks 210, Figs. 28 and 29, are provided to support the front of the trailer when the prime mover is disconnected. At the rear, the trailer is connected to an axle 94, Fig. 28a, having pivotally mounted thereon spindle arms 95 terminating in spindles 96 provided with wheels 97. The spindle arms 95 are connected with a tie rod 98 and hydraulic cylinders 99 which simultaneously pivot the spindles 96 around their pivot points 100 to facilitate transversing narrow, winding roads and sharp curves. Securely fastened to the tie rod 98 connecting the spindle arms 95 is a yoke or bracket member 101 terminating in end sections 102 freely movable across a plate 103 secured to the axle 94. Apertures 104 are provided in the ends 102 of the bracket member 101 and in the plate 103 which are adapted to receive a retaining pin 105 when the apertures 104 are aligned to lock the tie rod 98 in a position such that the spindle 96 connected thereto are locked in alignment with the axle 94.

Suitably mounted below the deck of the trailer by appropriate brackets, hanger straps and the like, all well known in the art, are the bridge operating mechanisms which include a power plant, hydrosteer mechanisms, and a control panel forming part of the deck and adapted to be pivoted to a vertical position for operation. The power plant may be of any desired type and of conventional design, but the preferred power plant is a constant speed internal combustion engine 110, Figs. 28 and 29. A fuel tank 111 for the engine is likewise mounted in the trailer body

beneath the deck. This power plant operably rotates reduction gears 112 which are connected through sprockets 113 and chains 114 to the mechanical winches 115 positioned in the trailer body. The winches 115 control the lowering and lifting cables 50, each of which has one end secured to a winch 115 and the other end secured to a lift bracket 45 or 45a in the bridge, Fig. 5.

A plurality of fluid pumps are connected with the power plant whereby the pumps are operably rotated to furnish pressure for the hydraulic systems as well as to operate the power plant accessories, such as the fuel pump, water pump and the like. One of the pumps 116 furnishes pressure for the hydrosteer mechanism and another pump 117 furnishes pressure for the hydraulic mechanism employed in lifting and lowering the bridge from the trailer body and opening and closing the far section of the bridge. The hydraulic launching mechanism comprises a pair of telescoping hoists 118, Figs. 30 to 33, inclusive, positioned in the rear section of the trailer body, and a centrally positioned hydraulic ram 119 having a sheave 120 attached to the longitudinally movable piston rod 121. It is contemplated that separate pumps may be employed with a common control valve or separate control valve for the hydraulic hoists and hydraulic ram.

In order to insure that proper and equal tension is exerted on each end of the opening cable 70 a housing 123 encasing the sheave 120 operated by the hydraulic ram 119, Figs. 28a and 29a, is provided with a sheave pin nut 124 having bearing surfaces 125 adapted to slidably contact guide members 126, Figs. 30 and 31, longitudinally positioned in the trailer body to prevent lateral sway motion of the sheave. To further guide the sheave 120 and prevent vertical sway motion thereof, parallel guide members 126a are positioned beneath the sheave housing thereby defining a channel or guideway with said first-mentioned guide members 126.

Positioned in the trailer body are two booms 128, Figs. 2 and 3, preferably formed of reinforced channel members pivotally mounted in a conventional manner near the rear of the trailer and positioned such that they are flush with the trailer deck when the telescoping hoists 118 to which they are attached, are fully collapsed. Reinforcing members 129, Fig. 29a, are secured to the inner surface of channel member booms 128 and provided with depressions 130, Fig. 29a, adapted to receive a projection 131 on the telescoping hoists 118 positioned therebeneath and mounted on brackets secured to the trailer beams. The projection 131 and sides of the booms 128 and reinforcing plate 129 are provided with apertures 132, Figs. 26 and 27, which receive a pivot pin 133 connecting the booms 128 and hoists 118 in operable relationship. The free ends of the booms 128 have wide faced sheaves 134 rotatably mounted therein, and a cross supporting grill 135, Figs. 2, 3, 26 and 27, connecting the otherwise free ends of the booms.

A control panel 140, Figs. 34 and 35, having two positions, horizontal and vertical, is provided near the front of the trailer. The control panel is pivotally secured to the trailer by a hinge 141 or hinges in a conventional manner, and may be locked in the vertical position in any suitable manner. However, a simple, inexpensive method has been devised whereby a saddle or channel member 142 is secured to the inner surface of

each side 143 of the control panel 140 and has rotatably mounted thereon a shaft 144 having a stud 145 adapted to project through an aperture 146 in the panel side member 143 and engage the top of the trailer deck when the shaft is rotated. Secured to or forming a part of the shaft is an elongated arm 147 which serves as a handle for rotating the shaft 144.

Securely fastened to the inside of the control panel 140 is a raised channel member 151, Figs. 35 to 37, inclusive, extending outwardly therefrom and adapted to receive a yoke support bracket 152 having spaced members 153 extending along the sides of said channel 151 and terminating in outwardly extending flanges 154. Two clamp plates 156 are positioned, one on each side of said raised channel member 151 and overlapping the flanges 154 of the yoke support bracket 152. Suitably positioned bolts 157, extending through the control panel 140 and clamp plates 156, clamp the yoke support bracket 152 in a predetermined position by the frictional engagement of the clamp plates 156 on the flanges 154 of the yoke support bracket 152. Thus, by loosening the wing nuts 158 on the bolts 157 the yoke support bracket 152 may be moved along the raised channel member 151. The yoke 160, forming an extension of the bracket 152, has securely positioned thereon the hydraulic actuating control means 161, the hydrosteer valve 162 and actuating wheel 163. The hydraulic actuating control means 161 comprises essentially a four-position valve selectively directing and releasing pressure for launching and lifting the bridge. Also positioned on the control panel 140 are the power plant starter 164, choke 165, throttle 166 and ammeter 167 mounted on a dashboard 168 secured to the panel 140. A bleeder valve 170 having a pressure meter 171 connected therewith is also suitably mounted on the control panel 140 for controlling the pressure in the hydraulic hoists 118. A clutch operating lever 172, Figs. 28, 29, 34 and 35, to release power from the reduction gears 112 when it is desired to run the power plant for operating only the hydrosteer mechanism during travel is likewise positioned on the control panel for easy access by an operator. Removably mounted to the trailer frame near the control panel is a winch operating handle 173 having three positions, that is, neutral, forward and reverse. A platform 175, Fig. 36, is provided for the operator and is pivotally secured to the trailer body at the rear of the platform in a conventional manner and links 176 are pivotally secured at one end to the front 55 of the platform and at the other end to the side 143 of the control panel 140. Thus, the platform 175 is held horizontal when the control panel 140 is vertically positioned and it is pivoted downwardly and out of the way when the control panel 60 140 is in the horizontal position forming a part of the trailer deck 148. The trailer deck 148 has portions thereof pivotally secured to the trailer body so that they may be pivoted out of the way to afford access to the power plant 110 and winches 115, Figs. 28 and 29.

The four-position hydraulic control valve 161, Figs. 34 and 35, has four connections, each connected through suitable means including flexible tubing with appropriate pipelines. One such connection 177 couples the pressure side of the hydraulic pump 117, Figs. 30 to 33, inclusive, with the control valve 161, another or second connection 178 couples the hydraulic ram 119 with the control valve 161, the third connection 179 couples the telescoping hydraulic hoists 118 with

11

the control valve 161 and a fourth connection 180 couples the control valve 161 with the hydraulic reservoir 181. The particular configuration and interconnecting portions of the hydraulic valve 161 are such that when the valve control handle 159 is in its innermost or first position the pressure is directed to the telescoping hydraulic hoists 118 raising the same, and releasing the pressure in the fore part of the hydraulic ram 119 to return through the hydraulic control valve 161 to the reservoir 181. When the valve is pulled outwardly to its second position pressure is sealed in the hydraulic hoists 118 holding them in that position and at the same time the pressure is released on the fore portion of the hydraulic ram 119 whereby the fluid may be returned through the valve 161 to the reservoir 181. Upon pulling the valve further outwardly into its third position pressure in the telescoping hydraulic hoist 118 is continued in its sealed relationship, and pressure is sealed in the hydraulic ram 119 holding it in its position. The furthermost and fourth position of the valve is such that the pressure is sealed to the hoists 118 and directed to the fore portion of the hydraulic ram 119 thereby forcing the piston 121 inwardly. Interconnecting the pipeline 179a to the hydraulic hoist 118 with the return line 189a to the hydraulic reservoir 181 is a flexible conduit 182 having positioned therein a bleeder valve 170 for controlling and releasing the pressure in the hydraulic hoist line 179a. Suitable relief safety valves 184 are positioned in pipelines 179a and 178a connecting the hydraulic ram and the hydraulic hoist lines, respectively, with the reservoir 181 through pipes 185 and 186 to overcome the danger of large pressures being built up in the hydraulic systems. Likewise a suitable connection 183 is positioned intermediate the reservoir and the suction side of the hydraulic pump 117 to complete the hydraulic fluid cycle. In order to avoid a hydraulic stop in the ram due to fluid leakage past the piston head, a return line 187 connects the rear portion of the ram 119 with the hydraulic reservoir 181.

The hydrosteer mechanism is of the sealed fluid type controlled by a valve 162, Figs. 34 and 35, having four connections, similar in principle to the structure disclosed in U. S. Patent No. 2,362,262 issued to H. C. French, 7 November 1944. One such connection 189 couples through suitable means including flexible tubing, the hydrosteer valve with the pipe 189a, Figs. 28 and 29, connected to the pressure side of the hydrosteer pump 116. The second, and similar connection 190 couples the hydrosteer valve 162 with the pipe 190a connected to the suction side of the pump 116. Of the other two connections, one 191 couples the hydrosteer valve 162 with the hydraulically actuated cylinder 99 on the right side of the hydrosteer axle 94 whereas the other 192 is connected to a similar cylinder 99 on the left side of the axle 94. Due to the configuration of the valve 162 and its opening and closing means, by turning the hydrosteer wheel 163 fluid pressure is directed into one of the hydrosteer cylinders 99 which in turn and through appropriate tie rod mechanism 98 pivots the spindles 96 in one direction; whereas, when the hydrosteer wheel 163 is turned in the opposite direction the pressure is reversed thereby turning the spindles 96 in the opposite direction.

To employ the weight of the prime mover 1 as a counterbalance when launching the bridge 3, a cable 107, Fig. 41, usually secured to the winch 108 on the prime mover is positioned beneath a

12

roller 109 aligned with the front beam of the trailer. This cable is then passed around an annular grooved member 106 and secured to the trailer frame. Thus, when tension is placed on the cable 107, a counterbalance couple is effected between the trailer 2 and the prime mover 1.

To effect a pivotal connection between the trailer and bridge, a pivot pin 194, Figs. 26 and 27, supported by a removable bracket 195 is secured at each side of the trailer to the rear cross beam 91 and outer longitudinal beam 90. The lipped groove pivot member 76 secured to the approach end of the bridge receives this pivot pin 194 and the pivotally mounted safety stop 80 is positioned across the groove opening, confining the pivot pin 194 to that closed portion of the groove behind the lip 79. Secured to the bracket 195 supporting this pivot pin is a plate 196 having a bearing surface; preferably in the form of a ball bearing race 197, Figs. 38 to 40, inclusive, mounted thereon. Mounted in this bearing race 197 is a cylindrical member 198 terminating in a similar bearing race 197 positioned in the outward longitudinal beam 90 of the trailer body. This cylindrical member 198 has a longitudinal portion thereof cut out to provide a slot 199 and a bracket plate 200 secured at each side of the slot 199. Suitably mounted upon a pin 201 secured to the bracket plates 200 is a sheave 202 extending inwardly of said cylindrical member 198. This mounting provides a swivel sheave having positioned thereon the opening cable 70 and accommodating the angle of rotation of the opening cable to direct the cable around another pair of sheaves 203 positioned interiorly of the trailer body and guiding the opening cable 70 around the sheave 120 secured to the hydraulic ram 119.

To absorb the load on the trailer tires when launching or retrieving the bridge, bracing pads 205, Figs. 2, 3, 26 and 27, are secured to the rear of the trailer. These pads may be any of the conventional type, but the preferred pad has two legs 206 and 207 pivotally connected to a foot 208 and pivotally connected to a rotatable member 209 mounted on the rear corner of the trailer. One of the legs 206 is adjustable to raise and lower the foot 208.

It is believed that the bridge 3, trailer 2 and prime mover 1 relationship and cooperation will be more fully understood from studying a complete cycle of operation starting with the bridge 3 folded upon the trailer 2 and continuing through the launching process to the final emplaced position; and the process of picking up the bridge 3 from an emplaced condition and continuing until the bridge 3 is again folded upon the trailer 2 ready to be moved. With the trailer 2 in mobile position the opening cable 70 should first be checked to see that it is secured to the opening cable brackets 68 and properly threaded through the sheaves 65, 120, 202 and 203, Fig. 4. The control panel 140 is pivoted into vertical position and locked. The bleeder valve 170, Figs. 30 to 33, inclusive, is opened with the hydraulic control valve 161 in the number two position. The rear launching or bracing pads 205 are positioned in contact with the terrain to absorb the additional stresses exerted upon the rear portion of the trailer during the launching process and provide lateral stability. With the power plant 110 started, the hydraulic control valve 161 is pushed into position one and the bleeder valve 170 is closed whereupon oil is directed through the pipeline 179a to the telescoping hydraulic hoists 118 which start raising the booms 128 and

the bridge 3 positioned thereupon. After the pivot end of the bridge sections have been raised a few feet, the hydraulic control valve 161 is pulled into position two whereupon the booms 128 are held in this position while the lift cables 50 are secured to the lift brackets 45 positioned near the hinge end of the near section 5 of the bridge. The hydraulic control valve 161 is again placed in position one whereupon the hydraulic hoists 118 continue pivoting the booms 128 and bridge 3 around their respective pivot points; and, when the lift cables 50 are placed under tension the winch operating handle 173 is pushed forward permitting the cables 50 to unwind from the winches 115. Since the mechanical winches 115 and hydraulic hoists 118 have their motion substantially synchronized, there will not be any undue stress placed upon either of the systems during this part of the operation. When the telescoping hydraulic hoists 118 have been fully extended, the booms 128 are positioned slightly beyond vertical and at this point gravity begins pulling the near leaf 5 of the bridge downward and the far leaf 6 of the bridge is thereby pivoted away from the near leaf 5. The hydraulic valve 161 is then pulled into position three to hold the boom 128 and the hydraulic ram 119 while a quick check is made to see if everything is in condition for further launching. Assuming that no adverse situation has arisen, the hydraulic control valve 161 is placed in position four and the winch operating handle 173 placed in the forward position whereupon the winches 115 slowly lower the near leaf 5 of the bridge while hydraulic pressure is conveyed through the pipeline 178a to the hydraulic ram 119 forcing the piston 121 inwardly thereby pulling the opening cable 70 attached to the far leaf 6 of the bridge. Since the motion of the winches 115 and hydraulic ram 119 are substantially synchronized, when the near leaf 5 of the bridge reaches the horizontal position the far leaf 6 of the bridge will be pivoted into the horizontal position thereby effecting a continuous surface. The hydraulic control valve 161 may then be placed in position three whereby the hydraulic booms 128 and ram 119 are held under pressure in their present relationship. The winches 115 continue to lower the bridge until the far leaf 6 contacts the ground or other abutment structure. The lifting cables 50 are then removed from the pivot end lifting brackets 45 and secured to the approach end lifting brackets 45a positioned near the bridge and trailer pivot. The opening cable 70 is detached from the bridge and, winches 115 reversed to lift the bridge slightly whereupon the safety stop 30 is released from its position restricting the groove opening 77. The pads 265 are removed from contact with the terrain, and the prime mover 1 pulled forward to disengage the trailer portion of the pivot from the bridge portion of the pivot. The forward action of the mechanical winches 115 is engaged to lower the near section 5 of the bridge to the ground or appropriate abutment structure. The lifting cables 50 are disconnected from the bridge and attached to the rear of the trailer frame. If necessary to widen the bridge to accommodate wider vehicles, the gear operating handles are engaged with the gear box 28 and turned in a clockwise direction thereby expanding the bridge due to the extensibility of construction of the floor beams 18.

In the process of lifting or retrieving the bridge, the gear operating handles are turned

in a counter-clockwise direction narrowing the width of the bridge, if it had been expanded. The lift cables 50 are again secured to the bridge. The winch operating handle 173 is placed in the reverse or winding position lifting the bridge so that it may be pivoted to the trailer. The winch operating handle 173 is then positioned in the center or neutral position to hold the bridge for securing the pivotal relationship between the bridge and the trailer. The pads 265 are placed in contact with the terrain and opening cable 70 secured to the bridge. The lift cables 50 are secured to lift brackets 45 near the pivot end of the near section 5. The winch operating handle 173 is positioned in the reverse or lifting position to lift the bridge and the hydraulic control valve 161 is placed in position two to hold the booms 128 and permit oil under pressure in the hydraulic ram 119 to be released through the control valve 161 to the reservoir 181. When the near section 5 of the bridge contacts the booms 128, the bleeder valve 170 is slowly opened to permit the hydraulic pressure in the hoists 118 to escape to the reservoir 181. Care should be taken to see that the hydraulic pressure in the hoists 118 is not released so rapidly that tension is relieved from the lift cables 50. Thus, by bleeding the hoists 118 by the bleeder valve 170 the bridge structure is slowly lowered to the deck of the trailer 2 in the last half of the retrieving process. It is now in position for moving to another location when it comes to rest upon the trailer.

When, due to the particular terrain features, it is desired to use the trailer as an approach ramp to the bridge, instead of disconnecting the bridge from the trailer, the trailer is disconnected from the prime mover.

In as much as tension remains in lift cables 50 because the far section 6 of the bridge contacts the far abutment structure, the counterbalance couple cable 107 and fifth wheel connection 92 are disconnected. The prime mover is then driven away, leaving the trailer in a raised position. By paying-out the lift cables 50, the front of the trailer is lowered to the ground. The bleeder valve 170 is opened to permit oil to escape from the hydraulic hoists 118 to the reservoir 181, when lift cables 50 are wound on the winches 115, thereby pulling the booms 128 over the trailer. The booms 128 lower flush with the trailer deck as the hydraulic fluid is permitted to escape from the hoists 118 to the reservoir 181. Of course, the lift cables 50 are detached from the bridge and wound on to the winches 115. The control panel 149 is lowered to its horizontal position flush with the trailer deck, and the pivotal sections of the trailer deck, pivoted over the power plant and winches.

Having thus described my invention, what I claim as new and wish to secure by Letters Patent is:

1. A mobile bridge comprising, in combination, a wheeled vehicle having a body frame, and pivot brackets secured at the rear of said vehicle body frame; a bridge comprising two half sections pivotally secured together, and pivot members secured to each of said bridge sections constructed and arranged in a manner such that the pivot members on the inner bridge section selectively cooperates with the pivot brackets on said vehicle frame to effect a pivotal joinder therebetween; hoist means positioned adjacent each side of said vehicle frame and adapted to rotate the bridge around the pivotal joinder with

the vehicle; and, means pivoting the bridge sections around the pivotal connection therebetween, said means including a cable having the ends thereof secured to one bridge section, and means selectively increasing and decreasing the length of said cable between the bridge and vehicle.

2. A mobile bridge comprising, in combination, a mobile launching structure having a pivot bracket secured thereto; a bridge comprising two half sections, means pivotally securing said half sections together, pivot members secured to at least one of said bridge sections and cooperating with said pivot bracket on the launching structure to effect a pivotal joinder therebetween; and a plurality of means positioned in said launching structure operably rotating said bridge sections around said pivotal joinders to selectively position the bridge in folded and extended conditions, said means including booms pivotally secured to the launching structure, hydraulically actuated telescoping hoists pivotally engaging said booms and operably rotating said booms around their pivotal connection with the launching structure, cables secured at one end to one half section of the bridge and at the other end to a winch, another cable having the ends thereof secured to the other bridge section and the center portion of said cable engaging a sheave secured to a hydraulically actuated ram, and means selectively directing and releasing hydraulic fluid under pressure to and from said hydraulically actuated mechanisms.

3. A mobile bridge comprising, in combination, a trailer including a frame supported at the rear end by wheels, booms pivoted near the rear of said trailer and having sheaves mounted in the free ends thereof, hydraulic hoists mounted in said trailer and pivotally connected to said booms, winches having cables thereon aligned with said booms, a hydraulic ram positioned in said trailer and having a sheave mounted on the longitudinally reciprocable piston of said ram, guide sheaves positioned in said trailer, swivel sheaves mounted on each side of said trailer, a cable threaded through said ram sheave, guide sheaves and swivel sheaves, and a power plant operating said winches, hoists and ram; a bridge comprising a near section pivoted to said trailer, a far section pivoted to said near section, brackets on said near section adapted to engage the winch cables, brackets on said far section adapted to engage the ends of said other cable; and said near section and far section of the bridge having extensible cross beams for selectively increasing and decreasing the width of said bridge.

4. A mobile bridge comprising, in combination, a trailer having a frame supported at the rear end by wheels, booms pivoted near the rear of said trailer, hoists mounted in said trailer and operably engaging said booms to rotate same; and, a bridge comprising a near section removably pivoted to said trailer and contacting said booms when pivoted over the trailer, a far section pivoted to said near section and contacting same when pivoted over the trailer, cables removably attached to said near section, a cable removably attached to said far section, and means controlling said cables to pivot the bridge sections around the pivotal joinders therebetween the bridge and trailer.

5. A bridge comprising two support members, each of said support members being provided with a pivot linkage whereby one portion of the

support member is pivotal with respect to another portion thereof, extensible, horizontal cross-members extending between a pair of support members and having the ends thereof secured to the pair of support members, means extending and retracting said cross-members, deck members positioned across adjacent extensible cross-members, and means pivotally attaching one pair of the support members to a bridge launching structure.

6. A bridge comprising two support members, each of said support members being provided with a pivot linkage whereby one portion of the support member is pivotal with respect to another portion thereof; extensible cross-members each including two beams rigidly secured to different support members, channel members secured to one of said beams and extending along the other beam which has a longitudinal slot provided therein, a shaft inserted through said slot and secured to said channel members, a gear box secured to said slotted beam and operating a screw shaft terminally attached to said channel members, deck members positioned across adjacent beams, and means pivotally attaching said support members to a bridge launching structure.

7. A bridge comprising two half sections, each section including two spaced principal load support members, extensible, horizontal cross-members connecting said support members, means extending and retracting said cross-members, means pivotally securing said sections together, and pivot means on the near section pivotally connecting the section to a launching structure.

8. A bridge comprising two half sections, each section including spaced principal load support members, extensible, horizontal cross-members connecting said support members, means extending and retracting said cross-members, means pivotally securing said half sections together, pivot members on one of the half sections having a lipped groove adapted to receive complementary pivot connecting means supported by a bridge launching structure to effect a pivotal joinder therebetween.

9. A bridge comprising two half sections, each having two spaced principal load support members, extensible, horizontal cross-members connecting said support members, means extending and contracting said extensible cross-members, means pivotally securing said half sections together in a manner such that the sections contact in folded and fully extended conditions, and pivot members secured to the near section of the said bridge and adapted to cooperate with complementary pivot members secured to a launching structure to effect a pivotal joinder therebetween.

10. A mobile bridge-launching structure for launching a sectional bridge, comprising a trailer having sheave-supporting booms pivoted near the rear end thereof and constructed and arranged to be flush with the trailer deck in one position, hydraulic hoists mounted beneath the trailer deck and pivotally connected to said booms to operably rotate same about its pivot, winches having load engaging cables thereon aligned with said booms, and a longitudinally movable sheave having a load engaging cable positioned thereon operable to open the sections of the bridge while the hoists raise the bridge.

11. A mobile bridge-launching structure for launching a sectional bridge, comprising a trailer including a frame supported at the rear end by 75 wheels, booms pivoted near the rear of said

trailer and having sheaves rotatably mounted in the free ends thereof, hydraulic hoists mounted in said trailer and pivotally connected to said booms, winches having load engaging cables thereon aligned with said booms, a hydraulic ram positioned in said trailer and having a sheave mounted on the longitudinally reciprocable piston of said ram, guide sheaves positioned in said trailer, swivel sheaves mounted on each side of said trailer, a load engaging cable threaded through said ram, guide and swivel sheaves, and a power plant operating said winches, hoists and ram, the said sheave mounted on the longitudinally reciprocable piston of the ram being operable to open the sections of the bridge while the hoists raise the bridge.

12. A mobile bridge-launching structure for launching a sectional bridge, comprising a trailer including a frame supported at the rear by wheels, booms pivotally mounted near the rear of said trailer and having sheaves rotatably mounted in the free ends thereof, hydraulic hoists mounted in said trailer and pivotally connected to said booms, winches having load engaging cables thereon aligned with said booms, a hydraulic ram positioned in said trailer and having a sheave mounted on the longitudinally reciprocable piston of said ram, guide sheaves positioned in said trailer, swivel sheaves mounted on each side of said trailer, a load engaging cable threaded through said ram, guide and swivel sheaves, a power plant operating said winches, hoists and ram, and pivot brackets adapted to have a bridge pivotally mounted thereon, the said sheave mounted on the longitudinally reciprocable piston of the ram being operable to open the sections of the bridge while the hoists raise the bridge.

13. A mobile bridge construction comprising, in combination, a mobile tractor vehicle adapted to be transported by a prime mover vehicle, a scissor-type bridge pivotally mounted on the tractor and comprising two half-sections pivotally connected together, actuating mechanism on the trailer for launching the bridge in open position across an open span in a terrain, the sections having extensible floor beams, and mechanism for extending the floor beams for adjusting the width of the bridge.

14. A mobile bridge comprising, in combination, a mobile vehicle, a scissor-type bridge mounted on the vehicle and comprising two sections, one being a near section and the other a far section, means pivotally securing the sections together, means on the vehicle for raising and lowering the near section, pivot assemblies having one part thereof secured to the said bridge and another part secured to the vehicle, and mechanism also on the vehicle for opening the far section of the bridge independently of the means for raising and lowering the near section.

15. A mobile bridge comprising, in combination, a mobile vehicle having a body frame, a scissor-type bridge comprising two half sections pivotally secured together, one section thereof being pivotally secured to the vehicle body frame in a manner such that the bridge may be positioned in folded condition upon the vehicle frame, hoist means carried by the vehicle and bridge constructed and arranged to raise the said bridge in folded condition from the vehicle frame and to rotate the bridge around the pivotal connection with the vehicle frame until the center of gravity of the bridge is beyond the pivotal connection, means secured to the vehicle frame for controlling the lowering of the bridge, and means carried by the vehicle frame and the bridge for rotating the bridge section around the pivotal connection therebetween to open the bridge while the hoist means raise the bridge, thereby providing a continuous plane surface when the sections are fully extended.

16. A mobile bridge comprising, in combination, a mobile vehicle having a body frame, pivot brackets secured to the body frame at the rear end thereof, a bridge mounted on the body frame and comprising two half sections, means pivotally securing the half sections together at a point beneath the bridge structure, pivot members secured to each bridge section and to the brackets in a manner such that the said pivot members selectively cooperate with the pivot brackets on the vehicle to effect a pivotal joinder therebetween, the pivot members including instrumentalities permitting uncoupling of the vehicle from the bridge when the bridge has been launched, and a plurality of means connected to the vehicle frame and to the bridge for rotating the bridge around the respective pivotal connections to selectively position the bridge in folded condition upon the vehicle and in extended position beyond the vehicle.
